UNITED STATES PATENT OFFICE.

WILLIAM C. FINCK, OF ELIZABETH, NEW JERSEY, ASSIGNOR TO THE ANCIENT ORDER OF FORESTERS OF AMERICA, OF BROOKLYN, NEW YORK.

DESIGN FOR A BADGE.

SPECIFICATION forming part of Design No. 23,342, dated June 12, 1894.

Application filed May 7, 1894. Serial No. 510,404. Term of patent 14 years.

To all whom it may concern:

Be it known that I, WILLIAM C. FINCK, a citizen of the United States, residing at Elizabeth, Union county, New Jersey, have invented a new and original Design for Badges, fully described and represented in the following specification and the accompanying drawing, forming a part of the same.

The leading feature of my design consists in a shield surmounted by an eagle with spreading wings the tips of which touch the heads of two flag staffs crossed upon the shield and bearing each a United States flag draped upon the shield and conceal the body of the same, with a central circular medallion upon the shield containing a representation of a stag's head, adjacent concentric segmental panels above and below such central panel, and a continuous band concentric therewith and joining the lower ends of the flag staffs which are extended below the shield for such purpose.

In the annexed drawing, which represents a face view of the badge, *a* is the shield of which the upper portion only is visible, and *b* the eagle surmounting the same.

c are the flag staffs carrying the flags *c'*, *d* the circular panel upon the shield, *e e'* the adjacent panels concentric therewith arranged above and below the same, respectively, and *f* the concentric band joining the lower ends of the flag staffs and terminating in the scrolls *f'*.

What I claim herein is—

The design for a badge substantially as herein shown and described.

In testimony whereof I have hereunto set my hand in the presence of two subscribing witnesses.

WILLIAM C. FINCK.

Witnesses:

IDA M. CLARK,
HENRY J. MILLER.
